UNITED STATES PATENT OFFICE.

FRITZ ECKHARDT AND MAX HOHNEKAMP, OF EISENACH, GERMANY.

SAFETY DEVICE FOR SERIES-CONNECTED INCANDESCENT ELECTRIC LAMPS.

Application filed July 16, 1926, Serial No. 122,980, and in Germany January 29, 1926.

This invention relates to incandescent electric lamps for series connection, to which an alternative current path to the filament is connected in parallel for the purpose of ensuring continuous operation, such that, should a filament be destroyed, the current path which has up to then not been conductive becomes conductive and assumes a resistance of about the same size as that of the filament which has ceased to function.

Our invention consists in using for establishing a parallel path, not only for the particular arrangement under discussion but for all kinds of parallel paths for the purpose of ensuring continuous operation, fine aluminium powder with loosely arranged particles separated by a thin insulating layer.

The powder should not be as fine as possible, a powder of a flaky nature, similar to graphite powder, being found preferable.

The aluminium powder may be used without any addition, the thin layers of oxide of the powder granules themselves forming the insulating layer. It may also be mixed with non-conductors in powder form. The powder may be used in the dry state or mixed with a sticky fluid or some other plasticising agent, for instance insulating varnish, as long as the admixture does not disturb the close but light contact between the separate granules coated with the thin insulating layer.

Preferably the means for ensuring the continuous operation according to the present invention as is well-known in the case of other types of safety devices, are housed within the lamps. The material being used in the form of powder enables it to be enclosed very simply in a chamber in the foot of the lamp, such that the powder directly connects together the lead-in wires passing through the chamber to the filament. Preferably the chamber should not be entirely filled with the powder, a small air filled space being left unoccupied. Dry, loose aluminium powder has been found particularly suitable for use in this manner.

Owing to their constructional simplicity the aluminium powder resistances have been found particularly suitable for small lamps, even for miniature lamps. According to the present invention these safety devices are to be used for Christmas-tree decorations and for advertising letters and advertising orna-

ments in which it has hitherto not been possible to use such safety devices.

The accompanying drawing shows various constructional forms of the invention, Figs. 1 and 1^a being an actual constructional form of a lamp containing a safety device according to the present invention, Fig. 2 an arrangement for Christmas-trees the safety device being indicated diagrammatically and Fig. 2^a a detail of Fig. 2.

In Fig. 1 of the drawing *a* is the glass bulb, *b* the neck of the bulb, *c* the so-called foot of the lamp, which supports the fused-in lead-in wires *d*. By a plug *f* of asbestos wool with a water-proof covering *g*, the foot of the lamp is closed to the outside. Dry aluminium powder *e* has previously been introduced into the hollow space thus formed, such that, after the lamp has been finished, a small air filled space *h* will remain.

Owing to its being in contact with the air, the aluminium powder becomes coated immediately with the well-known very thin, but close layer of oxide, which presents sufficient resistance to the individual voltage of 14 volts. When however on the filament *i* failing, the lamps are subjected to the total voltage, the thin layers of oxide between the powder particles are broken down and the powder acts as a substitute resistance for the filament. Should further lamps fail and the current consequently rise to an unpermissible extent, the aluminium resistance will suddenly lose its conductivity and will act as a cut-out.

Should the oxide layer be destroyed during the transport of the lamps or owing to vibration, it will be constantly formed again, as there is sufficient air in the space *h*, although the plug *f* closes the bulb in an airtight manner. The hollow space *h* also prevents the aluminium powder being pressed together excessively, when the plug *f* is inserted, and from being made conductive in consequence. On the other hand as is well known, the thickness of the layer of oxide on aluminium does not increase, so that the contact resistance always remains equal to the pre-determined resistance, which is necessary for proper functioning of the device.

In Fig. 1^a which only shows the small tube at the foot of the lamp with the powder contained therein to a larger scale, it is assumed that aluminium in powder form is used mixed with a non-conductive powder.

The coarse granules *k* represent the metal granules, while the fine granules *l* represent the non-metallic powder, for instance kaolin.

5. That the powder resistances burn out when overloaded and that their resistance as a whole does not increase to such an extent that the whole series continues to burn with a reduced current consumption, is probably 10 accounted for by the fact that in the first place there is an increase in resistance between the separate granules which are in particularly slight contact with one another, while the value of the total resistance remains 15 practically unchanged, whereupon the points of increased resistance become more heated and finally burn out, the air enclosed in the chamber probably also playing a part.

In Fig. 2, four lamps of the lighting system of a Christmas-tree are shown, *m* are the usual fittings for such an arrangement, the clamping devices of which are indicated by clips *n* and are connected in series by means of flexible leads *o*. The electrode wires *d* of the lamps have exposed parts *d'* within the foot of the lamp, which are connected together by the powder *e*, as is shown in Fig. 3^a.

What we claim is:

- 30 1. In an incandescent electric lamp for connection in series, a hermetically sealed air-containing hollow space within the foot of the lamp, lead-in wires for the filament extending through the said hollow space, a 35 normally non-conductive shunt to the filament constituted by a dry loose aluminium powder partially filling the said hollow space and having its granules in light contact with one another and with thin insulation 40 between them and in electric contact with the said lead-in wires, said shunt, on the filament being destroyed being capable of becoming conductive by the action of the total voltage applied to the series and of 45 bridging over the faulty places.
2. In an incandescent electric lamp for connection in series a safety device comprising a normally non-conductive shunt to the filament of the lamp capable on the fila-

ment being destroyed of becoming conductive by the action of the total voltage applied to the series and when thus rendered conductive of bridging over the faulty place, the shunt being constituted by aluminium in powder form having its granules in light contact and thin insulation separating the granules.

3. In an incandescent electric lamp for connection in series a safety device comprising a normally non-conductive shunt to the filament of the lamp capable on the filament being destroyed of becoming conductive by the action of the total voltage applied to the series and, when thus rendered conductive, of bridging over the faulty place, the shunt being constituted by aluminium in powder form having its granules in light contact and a thin insulating coating of aluminium oxide separating the granules.

4. In an incandescent electric lamp for connection in series a safety device comprising a normally non-conductive shunt to the filament of the lamp capable on the filament being destroyed of becoming conductive by the action of the total voltage applied to the series and, when thus rendered conductive, of bridging over the faulty place, the shunt being constituted by aluminium powder mixed with a plasticising agent and having its granules in light contact and thin insulation separating the granules.

5. In a series of incandescent electric miniature lamps combined to form a Christmas tree illumination, a safety device for each lamp, this safety device comprising a normally non-conductive shunt to the filament of the lamp, capable on the filament being destroyed, of becoming conductive by the total voltage applied to the series and when thus rendered conductive of bridging over the faulty place, the shunt being composed of aluminium powder and being contained in the interior of the lamp.

In testimony whereof we have signed our names to this specification.

FRITZ ECKHARDT.
MAX HOHNEKAMP.
